ATTORNEYS

UNITED STATES PATENT OFFICE.

JOSEPH GOLTSTEIN, OF LIEGE, BELGIUM.

LOCK FOR FIRE-ARMS.

SPECIFICATION forming part of Letters Patent No. 351,262, dated October 19, 1886.

Application filed March 9, 1886. Serial No. 194,514. (No model.) Patented in Belgium October 30, 1885, No. 70,679.

To all whom it may concern:

Be it known that I, JOSEPH GOLTSTEIN, a resident of Liege, Kingdom of Belgium, have invented an Improvement in Fire-Arms, (for 5 one portion only of which I have obtained Letters Patent in Belgium, dated October 30, 1885, numbered 70,679,) of which the following is a complete specification, reference being had to the accompanying drawings, in which—

10 Figures 1, 2, and 3 represent side views, partly in section, of those parts of a fire-arm to which my invention relates. Fig. 4 is a similar view of a modification of the same.

This invention relates to an improvement in 15 the connection of the mainspring of a fire-arm with the hammer and with other parts, by which its action is modified from time to time, the object being, principally, to cause the said mainspring to automatically bring the hammer to a full-cock and hold it there at all 20 times, except while the user is aiming and firing.

The invention consists, principally, in causing 25 both arms of the mainspring to act on the hammer alternately, and in combining it with means for controlling its several actions upon the hammer.

The invention is applicable to all kinds of 30 fire-arms—such as rifles, shotguns, revolvers, and the like—and may be used on fire-arms having their hammers exposed, and also on those whose hammers are entirely concealed from view. In the drawings the latter class of arms alone is represented.

35 In these drawings, A represents the breech-piece of the fire-arm, and L the firing-pin.

B is a hammer, pivoted as usual, and connected with the upper wing, a, of the mainspring C by a link, b. The lower wing, d, is 40 adapted to rest on the shank e of the hammer. The wing a has a tendency to throw the hammer B against the firing-pin, as in Fig. 3, and the wing d has a tendency to draw the hammer B away from the firing-pin, as in Figs. 1 and 2.

45 In the breech-piece A is pivoted, at f, a lever, D, which connects by a link, g, Fig. 3, with the lower wing, d, of the mainspring C. The link g can be dispensed with, as in Fig. 4, 50 where a friction-roller, g', is shown as interposed between the parts D and d. The lever

D is at h jointed or otherwise connected to a hand-piece, E, which at its rear portion connects with a sliding pin, F, that enters a socket in the stock or breech-piece A.

55

G is a trigger, engaging the hammer in the ordinary manner, H the trigger-plate, and M the guard.

By the act of firing the hammer is thrown against the firing-pin L, as in Fig. 3, and immediately upon the hand-piece E being released the lower part or wing, d, of the mainspring presses or crowds the lever D downwardly, (see Fig. 1,) and by its contact with the shank e of the hammer throws the latter to the position of full-cock, in which it is locked by the contact of the lever D with the trigger G. The parts are now in the position shown in Fig. 1, and remain in this position until aim is taken. It will be seen from Fig. 1 that the pin f is in 70 this position drawn partly out of its socket.

By taking the gun in hand and drawing it against the shoulder the manipulator presses with the right hand on the hand-piece E, drawing the same backward into the position 75 which is shown in Fig. 2. By this act the lever D is turned on its pivot, so that it will raise the lower wing or part, d, of the main-

spring off the hammer. The hammer is now only held by the trigger, and only connected 80 with the upper wing or part, a, of the mainspring, which has a tendency to throw it against the firing-pin. The arm is now ready for the discharge, which takes place immedi- 85ately the trigger G is touched, whereupon the hammer is thrown forward, as in Fig. 3. As

soon as the manipulator ceases pressing the hand-piece E backward the lower wing of the spring d, which now bears on the shank of the hammer, will throw the latter into the position of full-cock, as in Fig. 1. In order to enable this to be done, the lower wing or part, d, of the spring is made much more powerful than the upper wing or part, a, because the resistance of the part a must be overcome by 95 the part d in order to bring the hammer from the position shown in Fig. 3 into that shown in Fig. 4.

90 Instead of making the parts a d in one piece, as shown, they may be made in two pieces, as 100 indicated in Fig. 4.

I claim—

1. In a fire-arm, the combination of the lever D with the spring d and trigger G, and hammer B, said spring being placed behind the hammer and over said lever, so that it will be strained by the action of the hand upon the lever D, as specified.

2. The combination of the hammer B with the link b, spring C, having two wings, a d, the link b joining the hammer to the wing a, lever D, connecting with the wing d, trigger

G, hand-piece E on lever D, and guide-rod F on hand-piece E, all arranged so that the main-spring is strained by the action of the stronger portion of the hand on the hand-piece E, leaving the trigger-finger free to perform the lighter action of pulling the trigger. 15

JOSEPH GOLTSTEIN.
